Primary Examiner — Michelle E. Wilson*Assistant Examiner* — Clese Moore, Jr.(74) *Attorney, Agent, or Firm* — The Dobrusin Law Firm, P.C.(57) **CLAIM**

The ornamental design for a floor mat, as shown and described.

DESCRIPTION

FIG. 1 is a perspective view of one embodiment of the present design.

FIG. 2 is a front elevational view of FIG. 1.

FIG. 3 is a top elevational view of FIG. 1.

FIG. 4 is a rear elevational view of FIG. 1.

FIG. 5 is a bottom elevational view of FIG. 1.

FIG. 6 is a first side elevational view of FIG. 1; and,

FIG. 7 is second side elevational view of FIG. 1.

The broken lines which define the bounds of the claimed design form no part thereof and are used to show environmental structure.
